ROLLED MATERIAL CUTTING TABLE

Frederick A. Lang, Tacoma, Wash.

Application May 24, 1941, Serial No. 395,115

6 Claims. (Cl. 242—55.4)

This invention relates to store furniture and especially to means for containing a plurality of rolls of material, such as window screening, of various widths, mesh, or kind, and for cutting any desired length, within the capacity of the device, from a selected roll, without removing the roll from its container.

The objects of my invention are to provide a neat cabinet or counter adapted to hold the several rolls of material and to permit any one of said rolls to be partially unrolled upon a flat surface on which a measuring scale is marked, and wherein the edge of said flat surface forms a guide for the cutting instrument. Further objects are to provide an apparatus which saves much time and labor in its operation over former methods, and which does not require that the operator lift the heavy rolls.

I attain these and other objects by the devices and arrangements illustrated in the accompanying drawing, in which—

Fig. 1 is a plan view of my improved cutting table showing the sliding cutting table top slid to the left to uncover the fifth roll from the right and showing a portion of the screening from the said roll lying on said cutting table top a specified length, and the edge of the table top acting as a guide for the cutting instrument cutting the fabric; Fig. 2 is a side elevation thereof, showing a part thereof in section; Fig. 3 is an end view thereof; and Fig. 4 is a detail section showing the mounting of the sliding table top in the cabinet frame.

Similar numerals of reference refer to similar parts throughout the several views.

One of the problems of the usual hardware store is the convenient disposal of the many rolls of screening which it is necessary to keep available for immediate use during certain seasons of the year and also, at the same time, to keep a portion of the floor clear for the unrolling of any of the said rolls, in order to cut therefrom a measured part. Also it is eminently unhandy to have to lift said heavy roll from its container and lay it on the floor, and to measure therefrom the required portion, and difficult to cut said portion off along a line at right angles to its side edge. All of these objections to the usual method of handling this material have been successfully overcome by my improved cutting table.

Referring now to the drawing, it will be seen that the cabinet comprises a base frame having a fixed top board 1, side boards 2 and end boards 3.

The top board 1 is provided with a series of slots 4 extending across it, at right-angles to the axis of the table. The side boards 2 extend up above the level of the top board 1, on each side, and are provided with grooves 5 on their inward edges and may be provided with metal strips 6 above said grooves 5.

A series of rectangular holes 7 are made in one or both of the side boards 2 immediately below the level of the top board 1. A lower board 8, substantially coextensive with the top board 1, is secured across the table frame and is positioned parallel with the table top board 1 and at a level below the lower edges of the holes 7. A series of vertical partitions 9 extend between the lower board 8 and the top board 1, across the table, 10 and positioned between the holes 7, thus dividing the space into a series of compartments under the top board, each of said compartments communicating directly with one of said holes 7. Each such compartment may be divided into two parts by means of cross partitions 10, if so desired.

The above-mentioned slots 4 in the top board 1, are each alined with the inner side of the corresponding partition 9 in such manner as to form 20 a continuous surface therewith. A thin sheet metal U-shaped holder 11 is secured in each of the above-described compartments and has its end extending up into the corresponding slot 4, each such holder 11 being adapted to receive a roll 12 of wire netting or other rolled material; 25 said roll 12 being inserted into the compartment through the hole 7 in the side board 2.

It will be observed that the slots 4, in the top board 1, to the right of the longitudinal center 30 of the cabinet, as viewed in Fig. 2, are on the right-hand side of the corresponding compartments and that those to the left of the said center are positioned on the left side of their corresponding compartments.

35 A sliding cutting table 13 is mounted above the fixed board 1, with its edges mounted in the above-described longitudinal grooves 5 (Fig. 4), and is adapted to slide freely therealong in either direction. The ends 14 of the cutting table 13 40 form the guides for the cutting instrument and are at right-angles to its side edges and may be lined with a metal protecting strip 15 to prevent the wear of said edges by the screening 12 as it is pulled over its edge and by the cutting instrument used for cutting the screening.

45 A pair of reversed measuring scales 16 and 17 are inset into the surface of the cutting table 13, the scale 16 marking distances from the left while the scale 17 marks distances from the right.

50 A series of additional compartments 18 may be made in either end wall 3 (Figs. 2 and 3) adapted to receive rolls of screening of such kinds as are not in general demand or are longer than the width of the table, and an extension holder 19 55 may be secured above such compartments 18 and positioned in line with the above described compartments of the cabinet, said holder being braced by the brackets 20. The ends of the holder 19 are entirely open so as to permit a long roll to be placed therein, one or both its ends extending beyond the ends of the holder 19.

A cover 21 for said holder 19 is provided, said cover being hinged at 22 to open upward in order to permit the ready insertion or removal of such a long roll therein.

In cases where the cabinet is of unusual length it is usually difficult to provide sufficient free space beyond each end of the cabinet to permit the long table 13 to be slid out from the ends one-half its length, in which case I provide one or more slots 23 (one only is shown) in the said table top 13, the unrolled screening being passed up through one of the said slots 23 instead of over the end edge of the table, as above described, thus making it unnecessary to slide the table 13 as far as would be necessary if such slots 23 were not provided.

My above described cutting table is operated in the following manner: When a certain width of screening is desired by a customer, for instance the roll 12 in the fifth compartment from the right-hand end of the cabinet, the sliding cutting table 13 is slid to the left until its right edge 15 has passed from over the slot 4 connecting to the said compartment; then the roll 12 therein is given a slight rotary motion in the compartment, by inserting the hand through the corresponding hole 7, to bring its end up through the slot 4; this end is then pulled, unrolling the said roll 12, and the unrolled screening is laid upon the cutting table 13 until it reaches the measure on the scale 17 corresponding to the customer's order. As the unrolled portion of the screening lies upon the table 13, the end thereof adjacent to slot 4 naturally bulges upward slightly, as seen in Fig. 2, and the cutting tool is slipped thereunder and then to the reenforced edge 15; the unrolled length is then firmly held by one hand with its longitudinal edge against the edge of the metal strip 6 and the cutting tool is guided by the metal edge 15, to cut the measured length of screening desired. The cut off portion may then be rolled and delivered to the customer, the roll 12 being given a slight turn to bring its new end back into the passage 4.

When one of the rolls in the end compartments 18 is to be cut, the cover 21 is turned upward on its hinges 22, to open the extension holder 19, and then the said roll is removed from its compartment 18 and laid in the extension holder 19. It is then drawn out therefrom to lie on the cutting table 13 which has, of course, been slid toward the right from its shown position. The above operation is then carried out to cut the desired length therefrom, and when completed the roll is returned to the compartment 18 from which it had been taken.

In the season when there is substantially no screening sold, the top board 13 of the cabinet, may be used as a display counter for the effective display of other goods being sold.

Thus it will be seen that I have invented a very neat cabinet in which such rolled material may be held in readiness for use and which is so simple in operation that much time and labor is saved over the usual method of operation.

It is to be understood that many changes may be made in the details of construction of my improved cabinet, without departing from the spirit of my invention as outlined in the appended claims.

Having described my invention, what I claim and desire to secure by Letters Patent, is:

1. In a rolled material cutting table, the combination of a holding cabinet; a compartment therein, extending transversely thereof, adapted

5 to hold a roll of material, and opening through the side of the cabinet; a passage through the top side of the cabinet and leading from said compartment and alined with one side thereof; and a sliding table mounted on said cabinet and above the top side thereof, and adapted to be slid therealong to expose the open end of said passage, whereby a roll of material held in said compartment may be partially unrolled therefrom to pass through said passage and to lie a measured distance upon said sliding table.

2. A cutting table as set forth in claim 1, wherein the end edge of said sliding table is at right-angles to the longitudinal axis of said cabinet, and is reenforced with metal, and is adapted to guide the cutting tool along the line at said measured distance from the unrolled end of said roll.

3. In a rolled material cutting table, the combination of a holding cabinet; a series of parallel compartments therein adapted to hold separate rolls of material and extending across the cabinet in a row, and opening through the side of the cabinet; a series of passages extending from one side of each of said compartments and leading up therefrom through the top of said cabinet; a sliding table mounted on said cabinet and above said compartments and adapted to be slid along said cabinet, to expose the open end of any of said passages, whereby a selected roll of material may be partially unrolled in said compartment and passed through said passage, and a measured length thereof laid on said sliding table, and whereby the edge of said sliding table forms a guide for a cutting tool.

4. A cutting table as set forth in claim 3, together with metal U-shaped holders, secured in said compartments and adapted to support the rolls therein, and positioned to guide the end of the roll upward through said passage.

5. In a rolled material cutting table, the combination of a holding cabinet; a plurality of compartments therein, each adapted to contain a single roll of material, and positioned side by side; a sliding table mounted on said cabinet and adapted to be slid in either direction over said compartments, whereby one or the other of its two ends will expose any of the said compartments; metal reinforcement on both ends of said sliding table; and a pair of opposed measuring scales inset in said sliding table, one said scale measuring from each end of said table, whereby a selected roll may be partially unrolled within its compartment and laid on said table a measured length from the edge of the table over which said unrolled material has been passed, and whereby said edge of the table is adapted to guide the cutting tool at said measured distance from the unrolled end of said roll.

6. In a rolled material cutting table, the combination of a holding cabinet of extended length; a plurality of compartments therein, each adapted to contain a single roll of material, and positioned side by side; a sliding table, coextensive with said cabinet and mounted thereon, and adapted to be slid in either direction over said compartments; a slot through said sliding table intermediate its ends, whereby any of said compartments may be exposed either by said slot or by either end of said sliding table, and whereby a roll of material in such compartment may be partially unrolled therefrom to pass above said table to lie a measured length upon said sliding table.
